UNITED STATES PATENT OFFICE.

CHRISTOPH HOTZ AND MARTIN CONRAD, OF CHICAGO, ILLINOIS.

WAGON-AXLE.

SPECIFICATION forming part of Letters Patent No. 388,975, dated September 4, 1888.

Application filed June 4, 1888. Serial No. 275,963. (No model.)

To all whom it may concern:

Be it known that we, CHRISTOPH HOTZ and MARTIN CONRAD, both of Chicago, in the county of Cook and State of Illinois, have invented certain new and useful Improvements in Wagon-Axes; and we do hereby declare that the following is a full, clear, and exact description thereof, reference being had to the accompanying drawings, and to the letters of reference marked theron, which form a part of this specification.

This invention relates to devices for more firmly securing skeins upon the arms of wooden wagon-axes; and it has for its object to provide a simple, effective, and conveniently-applied construction for this purpose, and one which also serves as a truss or strengthener for the axle.

The nature of the invention will be understood from the accompanying drawings and the following description.

In the drawings, Figure 1 is a side view of the principal part of the front axle of a heavy wagon, having the skeins secured thereon in accordance with our improvement. Fig. 2 is an under side view of the same axle. Fig. 3 is a detached view of the wrought-metal link which forms part of the fastening.

A represents a wooden wagon-axe; B, one of the two sheet-steel skeins covering the arms of the axle; B', the usual extension of the skein reaching inward over the side and under surfaces of the axle, and C a separate collar or huter-band clamped about the skein. To each of the extensions B' of the two opposite skeins is welded or otherwise united a bar, D, usually of thicker material than the sheet of which the skein is formed, and extending on the under side of the axle to within a short distance—say two or three inches, more or less—of the middle of the axle, said bar D forming a strong continuation of the extension B' of the skein. The free end of the bar D is turned outwardly or downwardly from the axle to form a short shallow hook, d, having a slight concavity on

that lateral surface thereof which is directed toward the skein to which it is connected. When the two skeins provided with bars D D are applied to the opposite ends of the axle, the free ends of said bars D D stand at a short distance apart, (desirably from four to six inches,) as shown clearly in both Figs. 1 and 2 of the drawings. After the skeins provided with these bars have been firmly forced upon opposite ends of the axle, in the usual way or otherwise, a wrought-iron or forged-steel link, E, Fig. 3, is dropped over the hooks d d while hot, and the sides of the link are then bent inward or downward, or both, so that the ends of the link will be drawn closely into the slight depressions of the hooks d d. The link is then allowed to cool, and in the cooling thereof said link by its contraction is made to tightly draw upon the opposite hooks, tending to retain the skeins securely in their place.

The device described may be applied to both front and rear axles, and in the front axle the space within the link between the hooks d d affords room for the protrusion of the king-bolt.

The construction described constitutes, as stated, a simple, inexpensive, easily-applied, and extremely secure device for the purpose had in view, and, moreover, serves to greatly strengthen the axle by its action as a truss.

We claim as our invention—
The combination, with a wagon-axe and opposite skeins, B B, thereon, of the bars D D, connected with the skeins and provided with hooks d d at their proximate ends, and a shrunk-metal link, E, embracing said hooks, substantially as described.

In testimony that we claim the foregoing as our invention we affix our signatures in presence of two witnesses.

CHRISTOPH HOTZ.
MARTIN CONRAD.
